UNITED STATES PATENT OFFICE.

HARRY E. EDWARDS, OF NILES, OHIO.

MACHINE FOR CHARGING AND DISCHARGING ANNEALING OVENS, ETC.

Application filed February 1, 1927. Serial No. 165,183.

This invention relates to machines for charging and discharging annealing ovens or the like.

One object is to provide a machine of this character which is especially designed for handling sheets of thin metal, such as tin plate in quantities, to elevate the same and carry them into an annealing oven under extreme heat and to lower the load to rest upon suitable supports within the oven, and then to be withdrawn from the oven, when the said sheets may be subjected to the necessary heat treatment therein to be later removed from the oven by the improved machine, in an obvious manner.

Another object is to provide a strong and durable machine which is capable of easily and uniformly lifting the excessive loads placed thereon with all friction reduced to a minimum and of transporting said load into the oven while the load is supported directly upon the axles of bearing wheels arranged in pairs and so shaped as to co-act with corresponding tracks to prevent all lateral movement or tendency to tilt, and at the same time to permit the loaded machine to be easily moved under power into or out of the oven.

A final object is to provide a charging and discharging machine which may be readily installed in front of an oven as one of a battery of such machines for tending a plurality of ovens, all of said machines being adapted to be moved into or out of the ovens by a common drive shaft having gear connections which may be arranged to simultaneously shift all of the machines, or to independently move the same, and each machine having separate controlling means at its rear end for raising or lowering the load thereon.

A full and complete understanding of the invention may be obtained from a consideration of the following detailed description, taken in connection with the accompanying drawings forming a part of this specification; it being understood that while the drawings show a practical form of the invention, the latter is not to be confined to strict conformity with the showing thereof, but may be changed or modified, so long as such changes or modifications mark no material departure from the salient features of the invention, as specifically pointed out in the appended claims.

In the drawings, in which similar refer-

ence characters designate corresponding parts throughout the several figures:

Figure 1 is a side elevation of the improved machine mounted for use in connection with an annealing oven.

Figure 2 is a top plan view of the same.

Figure 3 is an enlarged transverse section through the front end of the machine, and illustrating the means for moving the same into and out of the oven.

Figure 4 is a longitudinal sectional view through the rear portion of the machine, parts being omitted.

Figure 5 is a detail plan view of the base frame or carriage of the machine.

Figure 6 is a transverse sectional view taken on the line 6—6 of Figure 4, and looking in the direction of the arrow.

Figure 7 is a detail side elevation of one of the elevating bars of the machine.

The illustrated embodiment of the invention comprises a main frame or carriage of elongated form and adapted to carry stacks of sheet tin or other metal in its usual commercial size and form, though it is to be understood that said carriage may be of other size and proportions to adapt the same for handling other articles or commodities. The frame includes spaced, parallel side members, each of which is composed of a pair of sills of equal length and held in rigid, spaced relation to each other and extending from end to end of the frame.

The outer sills 1 and the inner sills 2, which are formed of suitable rolled or cast metal, are each provided with an upstanding flange 3 located at their inner, opposite faces, and a space or cavity 4 is provided by depending walls 5 formed on each of the sills. The inner and outer walls 5 are provided adjacent to their lower edges with spaced apertures located in exact transverse alignment, and adapted to receive a series of axles or spindles 6 rigidly held in their seats by set screws 6^a which are threaded up through apertures formed in the bottoms of the walls, as shown in Figure 3 of the drawings.

Mounted on each of the spindles 6 and abutting against the inner faces of the walls 5 is a pair of wheels 7, preferably formed of solid metal, and adapted to freely rotate upon the spindle and independently of each other. The wheels occupy the aforesaid space or cavity 4 at either side and have either peripheries formed into V-shape, the

peripheral edge being slightly rounded to co-act with tracks 9, having spaced grooves 10 for receiving the wheels to prevent any lateral movement of the same.

- 5 Rollers or bushings 11, formed of hardened steel, are located on the central portions of the spindles between the wheels to rotate independently thereof, and the said spindles are preferably bored longitudinally 10 to receive a charge of grease or other lubricant through the usual cup 12 located at the inner ends of the spindles, there being proper outlets to lubricate the wheels and rollers in a well-known manner.
- 15 The top walls of the outer sills 1 extend somewhat beyond the depending wall 5 thereof to provide seats 13 into which there are bolted or otherwise secured rack bars 14, having a continuous series of teeth 15 along 20 their lower edges which are engaged by gear wheels 16 mounted on a continuous line shaft 17, located beneath the tracks and in bearings 18 secured to the bottom of a pit or channel 19 formed in the floor, which is 25 preferably made of concrete, as clearly shown in Figure 1 of the drawings.

The tracks 10 extend into the door A of the oven B, and are suitably supported therein to stand the strain of supporting the 30 loaded machine when the latter is charging the oven. The tracks extend outwardly the full length of the machine or beyond the same, there being, as has been stated, a pair of tracks and a machine for each oven, so 35 that the line or drive shaft 17 is extended crosswise of the entire battery from any suitable source of power, and the machines may be all operated simultaneously to charge the ovens, etc., or, by suitable clutch 40 mechanism (not shown), the several pairs of gears 16 may be thrown into or out of connection with the line shaft, and the several machines made to operate independently.

45 The several spindles 6 held as described, by the set screws 6^a, serve to hold the inner and outer sills in proper spaced relation throughout the major portions of their lengths, and at their outer or rear ends the said sills are secured to a filler block or bar 20, and the two inner sills are joined together by a cross bar 21 located near their centers, and by a rear cross bar 21 located adjacent to their ends.

50 Mounted between the upstanding flanges 3 of the sills is a pair of load supporting and elevating bars 22, which extend from the front end of the frame to within a short distance of the rear end thereof, said bars 55 being freely movable up and down and to swing rearwardly but, by reason of the close contact with the inner faces of the flanges 3, all lateral movement is eliminated.

These bars rest on their under surfaces upon 60 the aforesaid rollers or bushings 11, so that

any weight placed upon the same is taken directly by the spindles and the wheels 7, the lower portions of the side faces of the bars being indented so as not to bear upon the bevelled upper portions of the several 70 wheels.

The supporting bars are provided on their under sides with a series of depending lugs or enlargements 23, there being an enlargement for each of the wheels, except the two 75 rear pairs of wheels, as shown in Figures 1 and 4 of the drawings. The enlargements have each an inclined cam face 24 on the rear side thereof, and a flat or horizontal face 25 on the bottoms thereof, and when the bars are at their lowermost positions, the beginning of said cam faces are close to the rollers 11 so that, when said bars are drawn or pulled rearwardly, in a manner to be described, the inclined surfaces immediately 80 begin to roll upon the rollers with the result that said bars are simultaneously elevated until the lower flat faces 25 are drawn onto the rollers, when the bars, together with any load placed thereon, will remain in said 85 elevated position.

The rear ends of the bars 22 are formed with upstanding projections 26 provided with suitable horizontal apertures for the 90 reception of the front ends of pull rods 27, which are flexibly connected thereto by vertical bolts 28, there being sufficient play where the rods fit in said apertures, and where the bolts 28 traverse the rods 27 to 95 permit the latter to partake of considerable 100 up and down rocking movement for a purpose to be explained.

The rear ends of the pull rods 27 extend somewhat beyond the rear end of the main frame, and are there joined together by a 105 cross head 29, suitable nuts being threaded on to the ends of the rods to maintain such connection. The cross head, which is in the form of a metal block, is provided in its front face with a central concave seat 30 into which loosely fits the correspondingly shaped end of a plunger 31, which projects from the rear end of a hydraulic cylinder 32, which rests upon a cradle piece 21^a at the rear end of the frame, and is suitably secured to the frame to rigidly fasten the 110 same in position.

At the front closed end the cylinder is provided with a head 33, having lateral extensions in which are formed upright slots 34 (see Figure 6), which are open at their upper ends, and which receive the pull rods and allow the latter to partake of the aforesaid rocking movement which is the result of 115 the upward movement of the bars 22 to which the front ends of the pull rods are connected while the rear ends of the rods move in a horizontal plane together with the cross head.

Substantially midway between the con- 120

nection 26 and the guide 34, each pull rod is provided with a stop collar 35 which, preferably, is adjustably secured to the same, and interposed between the collar and the said 5 guide, is an expansion spring 36, the said springs serving to maintain the contact between the cross head and the plunger 31, when pressure is released within the cylinder and said plunger moves forwardly, and said 10 springs also serve to cause the lifting and supporting bars 22 to ride forwardly and downwardly when the load thereon has been carried into the oven and is in position to be left therein.

15 Mounted on the base frame, in advance of the cylinder and upon a suitable supporting base, is a hydraulic pump of any desired form as indicated at 37, and said pump is adapted to be operated, preferably by an 20 electric motor 38, the fluid under pressure, being conducted to the pressure cylinder by a pipe 39, having a suitable control valve 40 therein.

With the machine withdrawn from the 25 oven, as illustrated in Figure 1 of the drawings, the sheet metal plates or other load, is placed crosswise upon the supporting bars 22, so as to rest equally thereon, said bars being in elevated position, as shown in Figures 1 and 4. By means of the gears 16 and 30 racks 14, either one or all of the machines, as stated, may now be moved into the oven or ovens B, the pressure being maintained within the cylinder or cylinders 32 serving to 35 hold the loads in elevated position with the flat faces 25 of the lugs or projections resting upon the rollers 11. When the carriage or frame is advanced fully into the oven, the pressure is released and the springs, by expanding, start the downward movement of the supporting bars along the inclined faces 40 24 to deposit the marginal portions of said sheets or other load upon suitable shelves 41, located within the ovens and at the sides 45 thereof. When the bars are lowered, the machine is withdrawn from the oven, and the baking or annealing process proceeds, after the door or opening A of the oven has been closed by suitable means (not shown).

50 From the foregoing, it is thought a full and comprehensive understanding of the invention and the operations thereof, may be had and it will be seen that a strong and durable machine has been provided which 55 is adapted to handle great quantities of sheet metal or other heavy loads to move the same into and out of ovens or the like, the lifting means at either side of the machine being caused to move simultaneously, and to uniformly 60 elevate or lower said load in removing or placing the latter upon the supports within the oven.

What is claimed is:

1. A machine for charging ovens or the 65 like comprising a movable base frame, anti-

friction devices carried by the base frame, load-supporting bars mounted over the base frame and having inclined cam surfaces on their under sides to ride on the anti-friction devices, a pressure cylinder mounted on the 70 base frame, arms connected to the supporting bars to move the latter longitudinally when the pressure is admitted to the cylinder to cause the bars to elevate a load thereon, and springs on said arms to retract the bars and 75 release the load.

2. In a machine for charging or discharging annealing ovens or the like, an elongated base frame or carriage adapted to be moved longitudinally into and out of said oven, 80 said frame comprising spaced, parallel side members rigidly held together, each member having spaced, parallel sills, transverse spindles mounted in the sills, spaced bearing wheels mounted on the spindles and having bevelled peripheries, a longitudinal track having parallel grooves for each series of wheels, rollers mounted on the spindles between the pairs of wheels, a longitudinal supporting bar mounted between each pair 85 of sills and having depending portions bearing upon said rollers, the rear sides of said portions being inclined to ride up said rollers and elevate the bars when the latter are moved rearwardly. 90

3. In a machine for charging or discharging annealing ovens or the like, a frame or carriage comprising parallel side members rigidly held together and each including a pair of spaced sills, spindles connecting said sills together, a pair of spaced bearing wheels mounted to rotate on each of said spindles, tracks adapted to the wheels to permit the frame or carriage to be moved into or out of the oven, a rack bar carried 100 by each of the side members, a transverse line shaft having gear wheels meshing with the racks to move the frame or carriage, load supporting and elevating bars mounted between the sills and over the spindles, rollers mounted on the latter between the wheels and supporting the bars, depending portions formed on the lower face of the bars between the wheels and having inclined rear faces to bear on the rollers, a hydraulic cylinder mounted on the rear end of the frame, means mounted on the frame for forcing fluid into the cylinder, and means connected to the rear ends of the bars to pull the latter rearwardly and cause the load supporting bars to be elevated when pressure is admitted to the cylinder and the inclined faces ride upon the rollers. 110

4. In a machine for charging or discharging annealing ovens or the like, a frame, means for moving the frame into and out of the oven, rollers mounted in the sides of the frame, opposite longitudinally-disposed load supporting bars mounted in the sides of the frame and having cam surfaces 125 130

on their under sides to rest upon said rollers, a pull rod flexibly connected to the rear end of each supporting bar, a transverse cross head connected to the outer ends 5 of the rods, a hydraulic cylinder mounted longitudinally on the rear end of the frame between the rods and having a plunger bearing rearwardly against the cross head, and means for forcing fluid into the cylinder to 10 move the supporting bars rearwardly and upwardly to elevate a load thereon.

5. In a machine for charging or discharging annealing ovens or the like, a longitudinally movable supporting frame having 15 supporting wheels mounted on tracks to be run into and out of the oven, opposite racks carried by the sides of the frame, a transversely disposed shaft located beneath the tracks and having gear wheels meshing with 20 the racks to shift the frame, spaced rollers mounted to independently rotate on the wheel spindles, a load supporting bar longitudinally mounted in each side of the frame, each bar having a plurality of spaced depending cam portions on its under side, said portions including an inclined rear face 25 to ride upon the rollers when the bars are longitudinally moved and a flat lower face to rest on the roller and hold the bar in 30 elevated position, a rearwardly-extending pull rod flexibly connected to the rear end of each bar, a transverse cross head connected to the rear ends of the pull rods, a cylinder longitudinally mounted on the 35 frame and centrally between the rods, controllable means for exerting pressure within

the cylinder, a plunger extending rearwardly from the cylinder, said plunger having a rounded end bearing against the cross head to allow the same to rock upwardly, 40 vertical guides mounted on the cylinder, said guides being traversed by the pull rods, stops mounted on said rods and expansion springs mounted on the rods between the guides and stops to return the supporting 45 bars to lowered position when pressure is released in the cylinder.

6. In a machine for charging and discharging ovens, a frame or carriage including side members rigidly connected together 50 at their central portions and rear ends to maintain them in spaced parallel relation, each side member comprising parallel sills having depending flanges, transverse spindles connecting the flanges and holding the 55 sills in spaced relation, spaced bearing wheels mounted on the spindles and having V-shaped peripheries, rollers mounted on the spindles between the wheels to independently rotate thereon, means mounted within the side members to bear and roll on the 60 rollers for shifting a load thereon, and tracks coacting with the wheels to permit the frame to be run into the furnace and having spaced, parallel grooves to receive the V-shaped peripheries of the wheels and prevent lateral movement of the frame or carriage.

In testimony that I claim the foregoing as my own, I have hereto affixed my signature.

HARRY E. EDWARDS.
